(57) **CLAIM**

The ornamental design for an assembled non-slip floor mat, as shown and described.

DESCRIPTION

FIG. 1 is a perspective view of an assembled non-slip floor mat showing the new design.

FIG. 2 is a front view of the assembled non-slip floor mat of FIG. 1.

FIG. 3 is a magnified front view of the section in callout A of the assembled non-slip floor mat of FIG. 2.

FIG. 4 is a magnified front view of the section in callout B of the assembled non-slip floor mat of FIG. 2.

FIG. 5 is a rear view of the assembled non-slip floor mat of FIG. 1.

FIG. 6 is a magnified back view of the section in callout C of the assembled non-slip floor mat of FIG. 5.

FIG. 7 is a magnified back view of the section in callout D of the assembled non-slip floor mat of FIG. 5.

FIG. 8 is a side view of the assembled non-slip floor mat of FIG. 1.

FIG. 9 is an opposite side view the assembled non-slip floor mat of FIG. 1.

FIG. 10 is a top view of the assembled non-slip floor mat of FIG. 1; and,

FIG. 11 is a bottom side view the assembled non-slip floor mat of FIG. 1.

Broken lines show environmental structure that forms no part of the claimed design.

1 Claim, 11 Drawing Sheets
